(57) **CLAIM**

The ornamental design for a shoe sole, as shown and described.

DESCRIPTION

FIG. 1 illustrates a perspective view of a shoe sole showing my new design;

FIG. 2 illustrates a side view of the shoe sole of FIG. 1;
FIG. 3 illustrates an opposite side view of the shoe sole of FIG. 1;

FIG. 4 illustrates a front view of the shoe sole of FIG. 1;
FIG. 5 illustrates a rear view of the shoe sole of FIG. 1; and,
FIG. 6 illustrates a top view of the shoe sole of FIG. 1.
The broken lines in FIG. 4 defines the boundary of the claimed design.

The broken lines and the area within, form no part of the claim.
